UNITED STATES PATENT OFFICE.

JACOB OTTO LUNDBERG, OF BORGE, NEAR FREDRIKSSTAD, NORWAY.

STEAM-INLET AND WATER-OUTLET OF DRYING-CYLINDERS.

1,331,994.

Specification of Letters Patent. Patented Feb. 24, 1920.

Application filed June 24, 1919. Serial No. 306,511.

To all whom it may concern:

Be it known that I, JACOB OTTO LUNDBERG, a subject of the King of Norway, residing at Torp, Borge, near Fredriksstad, Norway, have invented new and useful Improvements in Steam-Inlets and Water-Outlets of Drying-Cylinders, of which the following is a specification.

As will be known, the water outlet tube 10 in steam heated drying cylinders, for instance, such as are employed in paper machines, are often exposed to wear and tear, caused by the fact that this tube owing to incorrect mounting, expansion or for other reasons, is brought out of its concentric position and bears against the inner wall of the hot hollow cylinder shaft or trunnion. If the water outlet tube (the so called siphon tube) is damaged, the cylinder is filled half-way with condensing water, which involves an increased consumption of steam, danger of explosion, increased pressure of bearing with liability to getting hot, increased consumption of lubricant, and further, a greater motive force and increased consumption of felt, leakage around screws and packing, breakage of the cylinder shaft and consequently a cessation of work and expensive repairs. The position and the absolute tightness of the siphon tube, must therefore be under perfect control, in order to obtain a reliable and economical working of the device.

In the common steam- and water-box arrangement such control is difficult and expensive, and also entails considerable trouble and waste of time, because the steam- and condensing water connections as well as the fastening bolts of the box must be loosened.

These disadvantages are avoided by arranging the steam inlet and the water outlet of the drying cylinder in accordance with the present invention, which is shown in the accompanying drawing.

Figure 1 is a longitudinal section through one end portion of a drying cylinder provided with the improved device for coupling the steam and water conduits.

Fig. 2 shows on a larger scale a longitudinal section through the coupling device. The drying cylinder 1 has as usual a hollow end-shaft or trunnion 2 adapted to rotate in bearings (not shown). Through the trunnion 2 the water outlet tube 3 communicates with the interior of the cylinder, while steam is conducted into the interior of the trunnion

by means of a tube 10. The tube 3 may be a common siphon tube as shown in the drawing, or it may be connected to a scooping device (not shown) in the interior of the 60 cylinder, by means of which the condensing water in the lower part of the cylinder is taken up and let out through the tube 3.

According to the invention the outer end of the tube 3 is fastened concentrical with 65 the trunnion 2 in a flanged cap 4 or the like, on the outer side of the stationary box-shaped continuation 5 of the trunnion 2, so that the tube 3 with the cap 4 can be removed or replaced without any disconnection of the 70 tube conduits being necessary. The end of the cap 4 is closed by a member 4' in which is secured an observation glass 6.

The steam passes from the main conduit 7 through the lateral tube 8 into the box 5 and 75 then into the steam tube 10 through radial openings 9 in the same, whereupon the steam is conducted into the hollow interior of the trunnion 2 and thence into the drying cylinder 1. The condensing water in the cylinder 80 is conducted through the tube 3 out into the outer compartment 11 of the cap 4 and thence through conduit 12 in the box or coupling piece 5 down through the water conduit 13, through the condensing vessel 14 85 and out through the tube 15.

The tube 3 is at the inner end of the steam tube 10 supported by a ring 16 which is connected with the steam tube. This ring is formed in such a way as to deflect the steam 90 current, so that any injecting influence of the steam is made impossible, and the lubricant between the bearing faces 17 is prevented from being sucked into the cylinder together with the steam.

The construction here set forth renders a quick and easy control possible, as it is only necessary to loosen the cap 4 to which the siphon-tube is fastened, whereupon this is drawn out for inspection without any liability of displacement of the box. Furthermore, through the glass 6 of the cap 4 at the end of the siphon-tube it may easily be observed whether condensing water alone is passing through or whether steam also is 105 escaping, which latter fact indicates defects in the condensing vessel, whose correct function in this simple manner may be examined in a reliable way.

As previously stated the present construction also removes the disadvantages that lubricant from the bearing faces 17 of the

box is sucked into the cylinder. In the formerly known arrangements of the steam inlets, the straight steam jet exercised a sucking action upon the lubricant oil, which increased the consumption of lubricant. The most serious disadvantage was, however, caused by the fact that the oil in the interior of the cylinder formed a coating which obstructed the transmission of heat, thereby increasing to a considerable amount the consumption of steam. Another drawback was, that the condensing water carried oil into the boiler, whereby an insulating coating was formed, the consumption of coal increased and the boiler tubes destroyed because they became burned and crooked, thus involving danger of explosion.

Having now described my invention, what I claim as new and desire to secure by Letters Patent is:—

1. The combination with a drying cylinder provided with a hollow trunnion, of a steam inlet tube communicating with the interior of said trunnion, a water tube extending through said trunnion and steam tube and a deflecting member between the inner end of said steam tube and the water tube, said

deflecting member and tubes being rigidly secured in concentric relation to the cylinder.

2. The combination with a drying cylinder having a hollow trunnion, of a steam inlet tube communicating with the interior of said trunnion, a water tube extending through said trunnion and steam tube, and a deflecting ring surrounding said water tube and secured to the inner end of said steam tube, said ring and tubes being rigidly secured in concentric relation to the cylinder.

3. The combination with a drying cylinder having a hollow trunnion, of a removable cap for closing the end of said trunnion, a steam inlet tube and a water outlet tube secured in said cap and maintained in concentric relation with said trunnion, and a transparent member secured in said cap thereby to permit observation of said water tube.

In testimony whereof I have signed my name to this specification.

JACOB OTTO LUNDBERG.
